(57) **CLAIM**

The ornamental design for a tailgate, as shown and described.

DESCRIPTION

FIG. 1 is a front left perspective view of a tailgate according to the present invention.

FIG. 2 is a rear right perspective view of the tailgate shown in FIG. 2.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof; and,

FIG. 9 is a second front view of the tailgate shown in FIGS. 1-8, shown in use.

The broken lines depict unclaimed environmental subject matter.

1 Claim, 9 Drawing Sheets
